UNITED STATES PATENT OFFICE.

THOMAS WARREN TALIAFERRO, OF SOUTH OMAHA, NEBRASKA.

DESIGN FOR A SASH-HOLDER.

SPECIFICATION forming part of Design No. 29,287, dated August 30, 1898.

Application filed May 29, 1897. Serial No. 638,800. Term of patent 14 years.

To all whom it may concern:

Be it known that I, THOMAS WARREN TALIAFERRO, a citizen of the United States, residing at South Omaha, in the county of Douglas 5 and State of Nebraska, have invented and produced a new and original Design for Sash-Holders; and I do declare the following to be a full, clear, and exact description of the same, reference being had to the accompanying 10 drawing, forming a part thereof.

The accompanying figure shows a perspective view of my sash-holder, the leading feature of my design comprising an elongated wedge A, which is provided with the integral 15 extending cone C, which cone is positioned upon the inclined surface of the wedge, the

wedge further being provided with the ear B, my sash-holder comprising, essentially, an elongated narrow wedge which at its broadest end is rounded and at this end is provided 20 with the ear, as has been set forth.

Having described my invention, what I claim as new, and desire to secure by Letters Patent as a design for a sash-holder, is—

The design for a sash-holder as herein 25 shown and described.

In testimony whereof I affix my signature in presence of two witnesses.

THOMAS WARREN TALIAFERRO.
